CABLE BUSHING

George Carlson, Bridgeport, Conn., assignor to
General Electric Company, a corporation of
New York

Original application August 23, 1938, Serial No.
226,265. Divided and this application Febru-
ary 1, 1941, Serial No. 377,043

2 Claims. (Cl. 174—83)

This invention relates to a bushing for armored cables of the type employing a paper wrap in combination with a spiral metallic armor. This application is a division of my copending application Serial No. 226,265, filed August 23, 1938 for Armored cable construction, now Patent No. 2,246,124, dated June 17, 1941, and assigned to the same assignee as the instant application.

It is an object of the invention to provide an improved form of bushing which may be easily inserted beneath the armor of the cable to protect the underlying conductors and which is so constructed and arranged as to furnish an additional insulating medium between the conductors.

In the accompanying drawing Fig. 1 is a view of the bushing in assembled position on an armored cable; Fig. 2 is a sectional view through such a cable employing two conductors showing the manner of applying the insulating paper wrap; Fig. 3 is a sectional view through a modification of the cable employing three conductors; Fig. 4 is a sectional view through another modification of the cable employing four conductors; Fig. 5 is a perspective view of the improved form of bushing, and Fig. 6 is a diagrammatic view of the twisted conductors and paper wrap of the cable.

Referring to the drawing the numeral 10 refers to the improved form of armored cable shown most clearly by Fig. 1, the cable forming the subject matter of the aforementioned copending application Serial No. 226,265. In the form of the invention illustrated by Figs. 1 and 2 the cable employs two insulated conductors having conducting wires 11, each being insulated with a rubber compound 12 and an overall saturated braid 13. In the manufacture of the cable the individual insulated conductors are run through a twisting machine, together with a longitudinal strip of waxed paper 14, commonly known to the trade as kraft paper. Upon entering the twisting machine the individual conductors are twisted together about the longitudinal paper as an axis so that the paper is wrapped about the individual conductors in an S-form, as shown by Fig. 2. In this form a central portion of the paper wrap remains placed between each of the insulated conductors, as shown at 15, while the edges 16 of the paper wrap encircle the entire periphery of the insulated conductors and completely cover them. As shown diagrammatically by Fig. 6, the edges of the S-shaped paper wrap appear twisted as they cover the twisted

conductors. Inasmuch as the strip of paper 14 is fed into the twisting machine longitudinally and the conductors are twisted about the paper wrap, it will be apparent that the paper wrap 15 constitutes in effect a longitudinal wrap running lengthwise of the cable and having a length equal to the length of the cable. It will be seen that with the improved construction just described a considerable saving in paper is effected over those constructions in which the paper is wrapped spirally about the twisted conductors due to the fact that a single strip of paper is disposed longitudinally of the cable rather than a plurality of spiral wraps. The strip 14 is cut 15 of sufficient width to encircle completely the individual conductors when in the final twisted form.

Immediately after twisting together of the conductors and paper wrap the assembly is removed from the twisting machine and fed into an armoring machine which applies an interlocked spiral metallic armor 17 upon the assembly in overlapping convolutions such as shown at 18. Due to the fact that the longitudinal wrap 14 closely grips the periphery of each of the insulated conductors a twisted assembly of conductors is formed having a minimum uniform diameter because only a single layer of the paper 14 surrounds the insulation on each 20 of the conductors. This makes it possible for the armoring machine to apply an armor of minimum diameter evenly over the entire length of cable without variations in the tightness of armor on the conductor assembly. At the same 25 time the edges of the paper wrap encircling the conductors adequately protect them from damage during the armoring operation. Inasmuch as the diameter of the armor is reduced to a minimum by the reduced overall diameter of the twisted conductors and paper wrap a substantial saving is effected in the quantity of metallic armor used.

It will be apparent from an examination of Fig. 2 that the layer of paper 14 is disposed at all times between the individual conductors. Should the conductors inadvertently become crushed together during the armoring operations, thereby damaging the insulation on the individual conductors, the layer of paper will provide an additional insulating medium between the conductors capable of withstanding approximately 600 volts. It has been found that the provision of this additional insulating means between the conductors reduces by a substantial amount the number of "rejects" to be had in the

commercial lengths of cable, which in the case of cables employed with voltages of 110 to 600 are tested by placing a potential of 1500 volts across the conductors and between each conductor and the armor.

The S-shaped paper wrap constitutes a protective covering for the conductors which will not break or split transversely when the armored cable is subjected to sharp twists or bends. This result is attained by virtue of the fact that the conductors are twisted about the paper wrap thereby twisting the edges of the paper and giving a certain amount of play to the paper wrap. Such a desirable result could not be obtained, were a longitudinal wrap of plain paper applied in cylindrical form over both the conductors. By using the S-shaped wrap it is possible to manufacture a cable which will withstand severe twisting or bending without injury to the inner insulating and protective layer of paper or to the insulated conductors themselves.

In using the improved cable, a severed end of the armor is easily stripped by pulling the armor longitudinally of the cable because the convolutions of armor slide easily over the plain longitudinally disposed paper strip. This construction makes it possible to strip the cable quickly thereby saving considerable time in installing lengths of the cable. It is also a simple matter to remove the excess length of paper over the stripped end of the cable simply by tearing it off at the point at which the armor was severed.

It will be seen that by using a longitudinal strip of paper twisted together with the conductors to S-shaped formation in the combination with a spiral metallic armor that it is possible to secure an improved form of armored cable having the advantages above described. These advantages make for better electrical characteristics of the cable, a reduction in the cost of manufacture, and a greater simplicity and saving of time in the use of the cable by skilled electricians.

While the construction has been described thus far in connection with a two conductor cable, it will be apparent that the construction may be applied to cables employing a plurality of conductors equally as well.

In the modification shown by Fig. 3 a cable is employed having three conductors 19, 20 and 21. In this construction two of the conductors 19 and 20 are twisted together as a unit about the paper strip so that the paper strip is disposed in S-shaped formation about the two conductors 19 and 20 together and about the single remaining conductor 21. Cables having three conductors frequently have one of the conductors grounded or at a neutral potential. In such situations the longitudinal paper strip is disposed between the conductors of high potential to provide additional insulation; for example, in the construction of Fig. 3 either of the conductors 19 or 20 may constitute the neutral with the high potential existing between the remaining conductor and the conductor 21.

In the modification shown by Fig. 4 a cable is shown having four conductors 22, 23, 24 and 25. The conductors are twisted in pairs about the longitudinal paper strip 14 and if there is any difference in potential between the pairs of conductors, the paper wrap is placed between those pairs subject to the greatest difference in potential.

To protect the severed end of the armor from

damaging the insulation on the individual conductors, an improved form of bushing is placed over the end of the armor.

As shown by Fig. 5, the bushing 26 is of substantially cylindrical form and is slightly tapered and provided with a slot 27. The bushing may be made of insulating material such as sheet fiber. One edge of the bushing is bent inwardly to form a separating or dividing plate 28 which extends substantially across the diameter of the cylindrical bushing forming the compartments 29 and 30. The bushing is provided with an overhanging bead or edge 31.

In the use of the bushing it is grasped by the hand and inserted over the insulated conductors, which may pass through the compartments 29 and 30, and then pushed down firmly over the severed end of the armor. The bead 31 overlies the rough severed edge of the armor and forms a smooth surface upon which the insulated conductors may rest, while the wall of the bushing forms a liner for the end portion of the armor. The dividing plate 28 takes a position between the insulated conductors and effectively insulates them from each other.

It frequently happens that a careless workman, in severing the spiral armor preparatory to stripping a length of the cable, will inadvertently cut through the layers of insulation upon the inner conductors. When this happens it is likely that steel slivers or filings incident to severing of the armor will be embedded within the insulation surrounding the individual conductors, and thus cause a short circuit to develop between the individual conductors of the armored cable. In those cases where the insulation on the individual conductors has been damaged by the severing of the metallic armor, the dividing plate prevents any possibility of a short circuit occurring between the conductors at this point. The dividing plate provides an effective continuation of that portion of the paper strip which passes between the individual conductors and thus forms in effect a complementary extension of the S-shaped paper wrap at that point where the paper wrap has been torn off in preparing the cable for wiring.

What I claim as new and desire to secure by Letters Patent of the United States, is:

1. A bushing for use with a cable having spiral metallic armor and a plurality of conductors comprising a substantially cylindrical member of insulating material, said member having a slot in the periphery thereof and being formed with a dividing plate separating said member into two compartments for the reception of the insulated conductors as said member is disposed between said conductors and said armor, said member having a bead extending around the periphery thereof for engaging the edge of the armor on said cable.

2. A bushing for use with cable having a plurality of conductors and an over-all metallic armor comprising an insulating member of substantially cylindrical form provided with a diametrical dividing wall separating said member into two compartments, each compartment being adapted to receive one of the insulated conductors as said member is slipped over the conductors to a position beneath a severed end of the armor, said member having a bead engaging and overlying the severed end of the armor.

GEORGE CARLSON.
